FINGER RING

Robert B. C. Newcomb, 19852 Chadbourne Lane,
Santa Ana, Calif. 92705

Continuation-in-part of abandoned design application
Ser. No. 426,072, Dec. 19, 1973. This application Feb.
27, 1976, Ser. No. 662,157

Term of patent 14 years

Int. Cl. D11—01

U.S. Cl. D11—29

FIG. 1

FIG. 4

FIG. 2

FIG. 3

FIG. 1 is a top plan view of a finger ring showing my new design.

FIG. 2 is a front elevation view.

FIG. 3 is a side elevational view.

FIG. 4 is a perspective view.

This application is a continuation-in-part of Ser. No. 426,072, filed Dec. 19, 1973, and now abandoned.

I claim:

The ornamental design for a finger ring, substantially as shown.
